UNITED STATES PATENT OFFICE

2,658,239

COTTON GIN

Dewey D. Day, Dallas, Tex., assignor to The Murray Company of Texas, Inc., Dallas, Tex., a corporation of Delaware

Application October 16, 1950, Serial No. 190,401

9 Claims. (Cl. 19—59)

1

This invention relates to new and useful improvements in cotton gin moting devices.

One object of the invention is to provide improved moting means for cotton gins, whereby the percentage of motes and trash removed from the saw teeth is greatly increased.

A further object of the invention is to provide an improved moting arrangement wherein the upper chamber of the stand in the rear of the saws is shut off and provided with a controlled discharge to the mote hopper below, whereby more efficient moting is had.

Another object of the invention is to provide an improved moting device wherein motes and trash are efficiently removed from the saw teeth and certain light trash, which heretofore has been difficult to control, is cast from the saw cylinder and prevented from again being drawn back into the lint stream.

A still further object of the invention is to provide an improved moting device wherein a pair of moting rollers are mounted in sequence outwardly of the saw cylinder in rear of the latter, whereby a much higher percentage of motes and trash are permanently removed from the cotton.

A construction designed to carry out the invention will be hereinafter described together with other features of the invention.

The invention will be more readily understood from a reading of the specification and by reference to the accompanying drawings, wherein examples of the invention are shown, and wherein:

Fig. 1 is a transverse, vertical, sectional view of a cotton gin stand equipped with a moting device constructed in accordance with the invention.

Fig. 2 is an enlarged sectional view of a portion of the device.

Fig. 3 is an enlarged transverse, vertical, sectional view of the upper rear portion of a gin stand showing the moting device therein.

Fig. 4 is a partial view of the moting roller, partly in perspective and partly in section.

Fig. 5 is an end view of a gin stand, partly in elevation and partly in section, to show a modified form of the invention.

Fig. 6 is an enlarged transverse, vertical, sectional view of the upper moting section of the stand, and

Fig. 7 is a partial end elevation of the stand showing the damper adjusting means.

In the drawings the numeral 10 designates, in general, a gin stand having vertical end walls 11, a saw cylinder 12, an air duct 13, an air sup-

2

ply duct 14, an air nozzle 15 and a lint flue 16, leading from the saws. These parts are regular elements of an ordinary gin stand.

The improvement has to do with the disposal

5 of the motes, dirt and dust cast off the saws between the ribs 17 and a transverse stripper bar 18, mounted on top of the nozzle 15. The stripper bar is L-shape in cross-section, having the back of its upright leg contiguous to the saws and its horizontal leg directed outwardly over the nozzle. The upper edge portion 19 of the stripper bar is bent slightly toward the saw teeth and is reduced to an edge so as to better strip the motes and trash from the saw teeth.

15 A longitudinal mote plate 20 is mounted on the stripper bar and suitably secured across the angle of said stripper bar. The plate has its lower portion 21 curved downwardly so as to overhang the top of the nozzle 15, as well as to overhang the front of said nozzle. A pair of moting rollers 22 and 23, respectively, are mounted in the moting chamber. The front roller 22 is disposed concentrically to the upper transverse curvature of the plate 20.

20 Both rollers are journaled in the end plates 11 and the rear roller 23 is centered on an angle of about 45° below the roller 22. The roller 23 is about twice the diameter of the front roller 22, but they are both driven at about the same 25 peripheral speed and revolve toward each other so as to carry material downwardly therebetween. The rear roller 23 wipes up a curved shield 24 mounted in the gin stand, thus the only exit, downwardly, is in the space between the flights of the two rollers.

30 Each roller is of the usual construction, common in this art and includes elongate flexible flights 25, disposed longitudinally on its outer periphery. These flights are formed of rubberized strips, suitably secured along their inner edges to the roller so that their outer edges are free and flexible. The outer edges of the flights of the roller 22 wipe up the curved surface of the upper curved portion of the plate 20, thus 35 keeping the roller clean. Because of the direction of revolution of the roller 22 and its location, motes and trash thrown off the saws are prevented from lodging on the bar 19 and plate 20 and are cast, by said roller 22, into the stand 40 above the rear roller 23.

45 It is obvious that as the saws 12 revolve and carry the cotton lint between the ribs 17, the motes and trash are thrown off between the ribs and the stripper bar 18. It has been found that 50 some of the heavy motes are cast off under such

force as to carry them over both rollers and into contact with the back of the gin housing. Suction applied through conduit 15' induces air currents to flow downwardly between the rollers and through the duct 16' so that all of the motes and trash are drawn down into the hopper 26 below the roller 23 and carried out by the screw conveyor 27. While this downward suction is sufficient to keep the flights clean there is substantially no suction directly on the saws 12 10 because the air is drawn into the enclosure through the front of the gin between the saws and ribs and at the ends of the saw cylinder. Further, a suction is not exerted directly on the saw cylinder because the air is pulled over the 15 top of the roller 22, thus the lint of good quality is not removed from the saw teeth.

Tests have shown that by use of the invention, an increase by weight, of motes and trash removed, amounts to 50% and more. This increase 20 is made up largely of light trash, such as has been heretofore, very difficult to remove and which frequently found its way back into the lint stream. By providing the reduced upper edge 19 on the stripper bar, motes and trash which would otherwise be carried down by the saws is stripped off and cast by the roller 22, rearwardly.

In Figs. 5, 6 and 7, I have shown a modified form wherein the roller 23' is mounted closer to the 30 roller 22' so as to cause the edge portions of the flights 25 to wipe across each other and further to cause the motes and trash to be cast downwardly at the rear of the roller 23'. In this form the roller 22' is revolved in the same direction as the roller 22 in Fig. 1; however, the direction of rotation of the roller 23' (Figs. 5 and 6) is reversed so that the motes and trash are cast from the roller 22' onto the roller 23' and are carried down the rear side of the latter.

The roller 23' is revolved faster than the roller 22' so as to cause the edges of flights 25 of the roller 23' in passing upwardly to wipe the material from the edge portions of the flights of the roller 22'. This removed material is carried over and rearward by the flights of the roller 23'. In the rear of the roller 23' a damper 27 is hung from a transverse shaft 28 journaled in the end walls 11. The lower portion of the damper has a vertically curved apron 29, approximately 50 conforming to the arc in which the outer edges of the flights 25 of the roller 23' travel. The shaft 28 extends through one of the end walls 11 and has an adjusting lever 30 thereon, as is shown in Fig. 7. This lever engages a toothed segment 31, as is common in this art, whereby the damper is held in adjusted positions. By adjusting the lever 30, the apron is spaced from the edges of the flights so as to control the volume 60 of air discharged downwardly. Under some conditions the modified form is found more desirable.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. In a cotton gin stand, the combination of, ginning ribs, saws revolving between the ribs, an air blast nozzle adjacent the saws, an upper moting chamber open to the saws between the ribs and the nozzle, a pair of rollers disposed

transversely of the gin stand in the rear of the saws and constituting the bottom of the upper moting chamber, and a lower mote chamber in the stand below the rollers, one of the rollers being forward of the other roller and above the nozzle adjacent the saws and the other roller being in rear of the nozzle, said rollers coacting to carry motes and trash from the upper moting chamber to the lower chamber, and means between the top of the nozzle and the forward roller for stripping motes and trash from the saws.

2. A cotton gin stand as set forth in claim 1, wherein the stripping means includes a stripper bar adjacent the saws above the nozzle.

3. A cotton gin stand as set forth in claim 1 wherein the rollers have peripheral yieldable flights.

4. A cotton gin stand as set forth in claim 1, wherein one of the rollers is revolved at a higher rate of peripheral speed than the other roller and said rollers have longitudinal peripheral yieldable flights in wiping contact whereby the flights of the higher speed roller wipe the flights of the other roller.

5. In a cotton gin stand, the combination of, ginning ribs, saws revolving between the ribs, an air blast nozzle adjacent the saws, an upper moting chamber open to the saws between the ribs and the nozzle, a pair of rollers disposed transversely of the gin stand in rear of the saws and constituting the bottom of the upper moting chamber, one of the rollers being forward of the other roller, said rollers having longitudinal peripheral yieldable flights in wiping contact with each other, a damper contiguous to the roller at the rear of the upper moting chamber, means for adjusting said damper with relation to the rear roller to control the discharge of material downwardly from said rear roller, and a lower mote chamber below the rollers.

6. In a cotton stand, the combination of, ginning ribs, saws revolving between the ribs, an air blast nozzle adjacent the saws, an upper moting chamber open to the saws between the ribs and the nozzle, a pair of rollers disposed transversely of the gin stand in rear of the saws and constituting the bottom of the upper moting chamber, one of the rollers being forward of the other roller and above the nozzle, said rollers having longitudinal peripheral yieldable flights in wiping contact with each other, a damper contiguous to the roller at the rear of the upper moting chamber, means for adjusting said damper with relation to the rear roller to control the discharge of material downwardly from said rear roller, a lower mote chamber below the rollers, a stripper bar extending across the saws immediately above the nozzle, and an elongate mote plate along the bar and over the nozzle having a portion concentric to the forward roller.

7. In combination with the gin saws and air blast nozzle of a cotton gin, a pair of moting rollers disposed longitudinally one relatively above and in rear of the gin saws, one of the rollers being forward of the other roller and being spaced from the saws and above the nozzle, the other roller being rearward of the nozzle, and a stripper bar contiguous to the teeth of the saws and between the top of the nozzle and the forward roller, said rearward roller coacting with the forward roller to carry motes and trash downwardly in the gin.

8. The combination set forth in claim 7 including, a mote plate mounted longitudinally along the stripper bar and contacted by the forward roller.

9. The combination set forth in claim 7 including, a mote plate mounted longitudinally along the stripper bar, the forward roller having elastic longitudinal flights disposed to wipe the mote plate.

DEWEY D. DAY.
